UNITED STATES PATENT OFFICE.

HARRY DALITZ, OF CLEVELAND, OHIO.

DESIGN FOR A WINDOW-FASTENER.

58,219.

Specification for Design.

Patented June 28, 1921.

Application filed January 29, 1921. Serial No. 441,052. Term of patent 14 years.

To all whom it may concern:

Be it known that I, HARRY DALITZ, a citizen of the United States, residing at Cleveland, in the county of Cuyahoga and State of Ohio, have invented a new, original, and ornamental Design for a Window-Fastener, of which the following is a specification, reference being had to the accompanying drawing, forming part thereof, in which—

Figure 1 is a front view, Fig. 2 a vertical edge view, Fig. 3 a perspective view, and Fig. 4 an end view of a window fastener, showing my new design.

I claim:

The ornamental design for a window fastener, as shown.

HARRY DALITZ.
